UNITED STATES PATENT OFFICE.

HARRY P. BREITENBACH, OF GROSSE POINTE, AND EUGENE J. O'NEILL AND SAMUEL T. KAY, OF DETROIT, MICHIGAN, ASSIGNEES TO SAID HARRY P. BREITENBACH, EUGENE J. O'NEILL, AND SAMUEL T. KAY, TRUSTEES.

COLLAPSIBLE BED.

Application filed March 26, 1927. Serial No. 178,574.

Our present invention relates generally to collapsible beds, and has particular reference to a construction and mechanism for supporting and guiding the movement of such a bed 5 into and out of a closet.

Where collapsible beds are arranged and constructed in association with a closet wherein they are designed to be normally collapsed and concealed, it generally happens 10 that at least a portion of the bed will remain within the closet after the bed has been opened. If said portion of the bed be used as the head thereof, a highly undesirable condition obtains in that the head of the sleeper 15 is insufficiently exposed to obtain the maximum benefit of air and ventilation.

It is an object of the present invention to provide a bed construction wherein the bed may be normally positioned entirely within 20 a closet and at the same time automatically adjustable upon an opening thereof to bring the entire bed out of the closet and into the room.

It is an important object to provide such 25 an arrangement in a manner whereby the single operation of drawing the bed outwardly into the room will function automatically to withdraw the entire bed in this manner, no additional operations of pulling or adjusting being necessary.

Briefly, our invention contemplates the 30 provision of a longitudinal bed support normally positionable in a substantially vertical manner within a suitably sized closet, 35 and means for simultaneously (a) swinging said support outwardly about its lower end, and (b) causing said lower end itself to move bodily out of the closet.

We achieve this general purpose by the 40 provision of two cooperating levers or members, one of which serves as a carrier for the pivot for the lower end of the bed support, and the other of which serves the function of controlling the movements of the former. 45 In a preferred construction, the control lever is pivotally mounted to a fixed point upon the floor of the closet and for convenience sake, this lever will hereinafter be referred to by us as the "floor" lever. Similarly, the pivot carrier referred to may be in the form of a 50 lever pivotally supported within the closet

and upon a wall thereof, and for similar reasons, this member or lever will be hereinafter termed the "wall" lever.

One feature of our invention lies in the 55 provision of an arrangement wherein the bed support will engage the floor lever, and wherein this engagement has the following two important functions: (a) The movement of the bed support will cause a movement of the floor lever and hence a desired 60 movement of the wall lever; (b) the bed support will be braced and supported in a distinctive manner by the floor lever so that 65 a sustained condition of substantial balance is assured.

Other features of our invention lie in the 70 particular arrangements and constructions of parts and the manner of their cooperation, whereby the entire construction is one of extreme simplicity both from the standpoint of manufacture, installation, and operation.

For the attainment of the foregoing objects and such other objects as may hereinafter appear or be pointed out, we have illustrated 75 one embodiment of our invention in the accompanying drawings in which—

Fig. 1 is a side view of the mechanism embodying the features of our invention, it being understood that a symmetrical set of 80 mechanism is located adjacent to the other side of the closet;

Fig. 2 is a front view of the second set of mechanism not shown in Fig. 1, i. e., a view looking into the right-hand side of the closet; 85

Fig. 3 is a view similar to Fig. 1 showing the parts in an intermediate position; and

Fig. 4 is a similar view showing the parts in their working position.

Referring to the drawings, and particularly to Figs. 1 and 2, we have shown a closet having a side wall 10, a rear wall 11, and a floor 12, the side wall corresponding to the wall 10 and immediately in front of the observer having been omitted to disclose the interior of the closet. A triangular supporting bracket is first positioned within the closet and may comprise a base 13, a rear 14, and an oblique reinforcing member 15, this structure being suitably positioned in a fixed manner 95 within the lower corner of the closet.

It will be understood that a second set of

mechanism, as illustrated in Fig. 1, is arranged adjacent to the wall 10, these two sets being symmetrical and juxtaposed, and the description of one set being sufficient to disclose the nature of the other.

The forward end of the base 13 is preferably positioned at the extreme forward edge of the closet floor, and this forward end constitutes a pivot point 16 about which a floor lever 17 is designed to swing. The lever 17 may therefore be said to be pivoted at its lower end to a fixed point on the floor of the closet, and it will be observed that the lever 17 extends upwardly in a substantially vertical direction and is provided at its upper end with two spaced rollers 18 arranged in a substantially horizontal plane.

We will point out at this time that a bed support 19, preferably comprising the usual tubular element forming one longitudinal side support for the bed, is designed to be slidably positioned between the rollers 18. We will also point out that the floor lever 17 is designed to swing from a normal position as shown in Fig. 1 outwardly into an operating position as shown in Fig. 4.

The rear member 14 is of such a length that its upper end will be positioned at a distance from the floor substantially equal to the height which the bed support 19 is designed to assume when in operative position. A point on the member 14 is arranged to constitute a pivot point for a wall lever, this pivot point 20 being preferably arranged at the uppermost end of the member 14. The wall lever 21 normally extends from the pivot point 20 obliquely downwardly at an angle of approximately 45° so that its free end lies adjacent to the floor. The lever 21 is of such a length that in its normal position it will be disposed entirely within the closet whereas outward swinging thereof about the pivot 20 as an axis will serve to bring the free end entirely out of the closet. In the construction shown, the various parts are so designed that the lever 21 is of a length greater than the depth of the closet, and the dot and dash line 22 indicates the general path of the free end of this lever.

The rear or lower end of the bed support 19 is pivotally associated, as at 23, to the free end of the lever 21. This may be accomplished by providing an integral structure 24 which includes a socket for the reception of the end of the support 19. It will be noted that the latter is preferably arranged along a gradual double curve adjacent to its rear end so that it may position itself within the socket and at the same time pass between the rollers 18.

Our invention contemplates that a pull will be exerted upon the support 19 tending to draw it outwardly in a swinging direction about the point 23 as an axis. It will be observed that when this is done, the engage-

ment of the support 19 with the rollers 18 will cause the floor lever 17 to swing outwardly in a manner indicated by the dot and dash line 25. So that this outward swinging of the floor lever 17 may at the same time control the movement of the wall lever 21, a link 26 is provided extending between the free end of the lever 17 and a medial point 27 of the lever 21. In this way, an outward pull upon the support 19 will cause the latter to pivot about the point 23, while the point 23 will at the same time be made to move bodily out of the closet along the path 22.

These movements of the elements 17, 19, 26, and 21 are more clearly shown in Figs. 3 and 4, and it will be noted that in the ultimate position, wherein the bed is ready for occupancy, the support 19 is substantially horizontal and in substantial alignment with both the link 26 and the lever 21. These elements are retained in this position by the weight of the bed itself, it being understood that the end portion of the support 19 shown in the drawings is but a relatively small portion of the entire length thereof.

In Fig. 2, which is a view taken from the right of Fig. 1 and looking at the mechanism adjacent to the wall 10, one method of constructing and arranging the elements described has been shown. It will be noted that the lower end of the floor lever 17 is forked to provide two spaced bearing points 28 and 29, these portions being rotatably mounted upon a spindle or shaft 30 provided in the forward end of the member 13.

It will also be noted that the wall lever 21 is not directly behind the lever 17, and that the structure 24 therefore comprises an angular portion 31 the lower end of which is arranged to provide a bearing 32 and the upper portion of which is arranged to provide the socket hereinbefore referred to for receiving the end of the support 19. The bearing 32 is mounted upon a pin carried by the lower end of the lever 21, thereby constituting the pivot point 23 shown in Fig. 1.

It will also be noted that the link 26 is preferably provided with a forked upper end which provides two bearing portions 33 and 34, the latter being mounted upon a spindle or shaft 35 extending completely across the closet.

So that the manipulation of the bed will be one of substantial balance, a set of springs 36 is provided extending between the lower end of the lever 17 and a fixed point upon the structure 24. The latter fixed point is preferably provided in the form of a transverse beam 37 extending transversely across the closet and between the portions 24. Before explaining the functions and operations of the springs 36, we will point out that the support 19 will slide outwardly between the rollers 18 during its outward swing. In

other words, whereas a certain portion of the lower end of the support 19 is disposed between the pivot 23 and the rollers 18 when the support 19 is in its normal position as shown in Fig. 1, a much smaller portion of the element 19 lies between these points after the bed has been opened. This is due to the fact that the pivot point 23 has changed its position relative to the pivot point 16, and consequently the support 19 will have moved outwardly in a slidable manner during the opening of the bed. Incidentally, this outward sliding of the support 19 will bring the rollers 18 adjacent to the end of the socket after the bed has been opened, this disposition of the elements being clearly shown in Fig. 4.

When the elements are in their normal collapsed positions as shown in Fig. 1, the support 19 is in a substantially vertical disposition, its weight being supported upon an adjustable block 38 provided on the portion 13. When the support 19 is pulled outwardly, its center of gravity will shift to the right, and the rollers 18 will assume the functions of fulcrums. In the absence of the springs 36, the support 19 would tend to fall outwardly, swinging about these fulcrums, because of the ever increasing lever arm between these fulcrums and the center of gravity. By providing the springs 36, this tendency to fall outwardly is counteracted, and the springs are so arranged, both as to strength and disposition, that the support 19 will be in substantial balance during all portions of its movement.

In the drawings, we have also illustrated the possible arrangement of a bracket 39 pivotally supported upon the shaft 35 and designed to carry the head end of the bed, this head end being indicated by the reference numeral 40.

We have also indicated a possible arrangement of trip lever for assuring the positive opening of the lower legs of the bed, these legs being not shown in the drawings but being operatively associated with a beam 41 extending rearwardly into pivotal association with the end of one arm of a bell crank lever 42. The latter is pivotally mounted as at 43 to a fixed point upon the structure 24, and is provided with an actuating arm 44. Actuation of the arm 44 will swing the bell crank lever 42 about the pivot 43 and will reciprocate the beam 41 longitudinally of the bed. This reciprocating movement may be made to control the opening and closing the lower feet of the bed, the beam 41 being shown in its normal position in Figs. 1-3, and being shown in its operating position in Fig. 4.

It will be obvious that many changes in the details herein described and illustrated for the purpose of explaining the nature of our invention may be made by those skilled in the

art without departing from the spirit and scope of the invention as expressed in the appended claims. It is therefore intended that these details be interpreted as illustrative, and not in a limiting sense. 70

Having thus described our invention and illustrated its use, what we claim as new and desire to secure by Letters Patent is—

1. In a collapsible bed construction for association with a closet, a longitudinal bed support normally positionable in a substantially vertical position within the closet, a pivot for the lower end of said support to permit the latter to be swung outwardly about said pivot, and means operable by so swinging the support for moving said pivot bodily out of the closet during the swinging operation, said means comprising a movable carrier lever for said pivot, a movable floor lever engageable by the support during its outward movement, and means operatively interposed between the floor lever and said carrier lever for causing the latter to move when the floor lever is moved. 75

2. In a collapsible bed construction for association with a closet, a longitudinal bed support normally positionable in a substantially vertical position within the closet, a pivot for the lower end of said support to permit the latter to be swung outwardly about said pivot, and means operable by so swinging the support for moving said pivot bodily out of the closet during the swinging operation, said means comprising a wall lever pivoted within the closet and carrying said bed support pivot, a floor lever pivoted to the floor of the closet and engageable by said support during its outward movement, and a link between the floor lever and the wall lever for causing pivotal movement of the latter 100 when the floor lever is moved. 105

3. In a collapsible bed construction for association with a closet, a floor lever pivoted at its lower end to a fixed point on the closet floor and normally in substantially vertical position within the closet, a wall lever pivoted at its rear end to a fixed point on the closet wall and so arranged that it may be made to assume either a normal position within the closet or a working position with its free end 110 out of the closet, means operatively interposed between the levers for projecting said free end out of the closet when the floor lever is pivotally moved, and a bed support pivoted at its rear end to said free end and arranged 115 to engage the floor lever. 120

4. In a collapsible bed construction for association with a closet, a floor lever pivoted at its lower end to a fixed point on the closet floor and normally in substantially vertical position within the closet, a wall lever pivoted at its rear end to a fixed point on the closet wall and so arranged that it may be made to assume either a normal position within the closet or a working position with its 125 130

- free end out of the closet, means operatively interposed between the levers for projecting said free end out of the closet when the floor lever is pivotally moved, and a bed support pivoted at its rear end to said free end and arranged to engage the floor lever, the latter being provided with a roller at its free end for slidably supporting the bed support thereon.
- 5 5. In a collapsible bed construction for association with a closet, a floor lever pivoted at its lower end to a fixed point on the closet floor and normally in substantially vertical position within the closet, a wall lever pivoted at its rear end to a fixed point on the closet wall and movable from a normal position within the closet to a working position with its free end out of the closet, a link between the floor lever and the wall lever for moving the latter into the working position when the floor lever is moved, and a bed support pivoted to said free end and arranged to engage the floor lever, whereby outward movement of the bed support will cause a pivoting thereof about said free end and will at the same time cause said free end to move bodily out of the closet.
- 10 6. In a collapsible bed construction for association with a closet, a floor lever pivoted at its lower end to a fixed point on the closet floor and normally in substantially vertical position within the closet, a wall lever greater in length than the closet depth and pivoted at its rear end to a fixed point on the rear closet wall, said wall lever being normally in an inclined position wholly within the closet, a link operatively interposed between the free end of the floor lever and a medial portion of the wall lever, and a longitudinal bed support pivoted at its rear end to the free end of the wall lever and slid-

ably supported forwardly of said rear end upon an axis movable with said floor lever.

7. In combination, a base having at the rear end an upright post, a bed adapted to be located in front of the base when in a horizontal position, a bar pivoted at one end to the post and at its other end to the bed, an arm pivoted at its lower end to the front end of the base and extending diagonally upwardly and forwardly to the bed when the latter is in a horizontal position, means connecting the upper end of said arm to the bed so as to permit it to slide lengthwise of the bed a limited distance and be held against movements relative to the bed in other directions, and a tension spring between the base and the adjacent end of the bed.

8. In combination, a base having at the rear end an upright post, a bed adapted to be located in front of the base when in a horizontal position, a bar pivoted at one end to the post and at its other end to the bed, an arm pivoted at its lower end to the front end of the base and extending diagonally upwardly and forwardly to the bed when the latter is in a horizontal position, means connecting the upper end of said arm to the bed so as to permit it to slide lengthwise of the bed a limited distance and be held against movements relative to the bed in other directions, means controlled by said bar for causing said arm to be swung rearwardly toward an upright position when the remote end of the bed is lifted, and a tension spring between the base and the adjacent end of the bed.

In witness whereof, we have signed this specification this 23rd day of March, 1927.

HARRY P. BREITENBACH.

EUGENE J. O'NEILL.
